CLAIM

The ornamental design for a wearable hand shape IV trainer as shown and described.

DESCRIPTION

FIG. 1 is a front, right and top perspective view of a wearable hand shape IV trainer showing my new design; FIG. 2 is a rear, left and bottom perspective view thereof; FIG. 3 is a front elevational view thereof; FIG. 4 is a rear elevational view thereof; FIG. 5 is a left view thereof; FIG. 6 is a right view thereof; FIG. 7 is a top plan view thereof; and, FIG. 8 is a bottom plan view thereof.

The broken lines illustrate portions of the wearable hand shape IV trainer that form no part of the claimed design.
